ELECTRICAL PLUG.

Application filed October 13, 1927. Serial No. 225,909.

This invention relates to electric plugs and plug receptacles and has for its object a plug which is particularly simple and economical in construction and consists of a small number of compactly arranged parts which are held assembled by a single fastening member.

5

The invention consists in the novel features and in the combinations and constructions hereinafter set forth and claimed.

10

In describing this invention, reference is had to the accompanying drawings in which like characters designate corresponding parts in all the views.

15

Figure 1 is a longitudinal sectional view, partly in elevation, of this plug, the contiguous portion of a plug receptacle being also shown.

Figure 2 is a sectional view, partly broken away, of parts of the plug shown in Figure 1, the component parts being shown as separated.

Figure 3 is an elevation, partly broken away, of a plug showing the locking means.

20 Figures 4 and 5 are, respectively, plan views of the blocks of insulation which support and retain the plug terminals in position.

Figures 6 and 7 are, respectively, a longitudinal sectional view and a plan view of a modified form of one of the sections of the plug.

This plug comprises generally, a case consisting of tubular sections, one telescoping within the other, plug terminals having wire engaging ends or binding devices associated therewith, supporting and retaining means for the plug terminals, the supporting and retaining means being slidably mounted in the case or the sections thereof and the plug terminals being slidably mounted in the supporting and retaining means, and means for locking the sections of the case and the parts within the same in assembled relation.

45 1 and 2 are, respectively, the tubular sections of the case, the section 1 telescoping within the section 2, the section 1 fitting within a socket S and the section 2 having a nipple for connection to a handle or other support through which the service wires extend. The service wires extending into the section 2 through the nipple 3.

4 designates the plug terminals and 5 is a grounding terminal. The plug terminals 55 4 are supported and retained in position by

blocks of insulation located, respectively in the sections 1, 2, there being one block in each section, and the blocks being slidable into the sections and the terminals slidable into the blocks.

60

6 designates the block of insulation in the section 1, this being formed with passages 7 therethrough in which the plug terminals 4 are located. The block 6 is located in the section 1 by an internal shoulder in the section 1, this shoulder being here shown as in the form of an inwardly extending lug 8 formed in the section 1 and fitting a complementary recess 9 in the block, the recess 9 opening through the inner end of the block 70 and terminating short of the outer end. The closed outer end provides a shoulder for abutting against the shoulder 8 and limiting the inward movement of the block 6 and hence determining the location of the block 75 6. The lug 8 is formed with a passage 10 in which the grounding terminal 5 is located.

11 designates the block within the section 2. This is also formed with passages for the terminals 4 or the wire receiving ends 80 thereof and also with a passage 12 for receiving the wire receiving end of the ground terminal 5. This block 11 also having an axial non-circular recess 13 which receives a projection 14 on the block 6. The recess 85 13 breaks through the walls of the terminal passages in the block 11 so that the recess 13 together with the passages in which the wire receiving ends of the terminals 4 are located, constitute a slot. The terminals 4 90 are held from endwise displacement by shoulders 15 thereon interposed between the blocks and these shoulders are located in recesses or countersinks 16 formed in the blocks or one of them. The shoulders are 95 non-circular or hexagonal and the recesses also are correspondingly shaped. Also, the ends of the passages 7 for the plug terminals in the block 6 are formed with countersinks for receiving interfitting projections 17 on 100 the block 11.

The block 11 slidably fits within the bore of the section 2 and abuts against an annular shoulder 18 which limits the inward movement of the block and thus determines 105 the position thereof.

The inner or wire receiving ends of the plug terminals 4 are preferably formed with axially extending bores 19 for receiving the ends of the wires and in which the wires are 110

soldered although as seen in Figures 6 and 7, these bores may receive threaded binding screws 20 located in recesses 21 in the block 22 corresponding to the block 11.

- 5 The means for holding the sections 1, 2 and the parts contained thereby in assembled relation is located within the section 1 and operable or accessible through the open end thereof. This means as here shown is a 10 wedge 23 which is operated into and out of wedging position by an operating member here shown as a screw 24 extending lengthwise through the block 6 with its head toward the outer end of the section 1, the 15 screw threading through the wedge and the wedge having a cam or inclined surface at one side coaxing at 25 with a similarly inclined plane surface on the block 6.

Obviously, during tightening of the screw 20 which threads into the wedge, the wedge due to the inclined surfaces will be forced laterally into snug engagement with the inner annular face of the section 1, this inner annular face being smooth or free from projections or obstructions.

The section 1 is formed with a slot 26 for permitting the wedge to engage the inner wall of the section 2. Preferably, the annular wall of the section 2 and of the wedge 30 nut coaxing therewith are slightly beveled.

In assembling, the service wires are passed through the nipple 3 and the block 11 threaded on the wires. The block 6 is placed in the section 1 through the outer end thereof 35 until it abuts against the shoulder and the plug terminals 4 and grounding terminal 5 placed in position therein and also, the wedge nut threaded on the screw 22 with the wedge in the slot 26. The wires are then 40 attached to the proper terminals 4, 5 and the block 11 moved along down to the wires into a position against the end of the section 1 and the sections 1 and 2 then brought together and the screw 24 tightened, the screw 45 24 and the wedge nut being the only fastening means required to hold all parts assembled except when the binding screws for the wires are used as shown in Figure 6.

The section 1 is provided with a suitable 50 external shoulder 28 fitting a complementary internal groove 29 in the section 1 for holding the sections from relative rotation. The section 1 is also provided with another external shoulder 30 for fitting a complementary 55 groove in the socket members in order to bring terminals of like plurality of the plug and socket into engagement.

The socket members may be of any suitable form, size and construction and is 60 formed with a suitable body 31 of insulation for fitting into the tubular section 1 and carrying socket terminals 32 for receiving the pronged ends of the plug terminals 4.

What I claim is:

- 65 1. An electric plug including a case com-

prising two tubular sections, one telescoping into the other, the outer section having an unobstructed bore for receiving the inner section telescoping thereinto, and means located entirely within the sections for securing them together, said means including an operating member accessible through the open outer end of the inner section.

2. An electric plug including a case comprising two tubular sections, one telescoping 75 into the other, the outer section having an unobstructed bore for receiving the inner section telescoping thereinto, and means located entirely within the sections for securing them together, said means comprising a 80 wedge carried by the inner section and coacting with the inner smooth bore of the outer section, and an operating member for the wedge accessible through the open outer end of the inner section.

3. An electric plug including a case having tubular telescoping sections, a block of insulation slidably mounted in the inner section and having passages therethrough, plug terminals extending through said passages and provided with means for engaging the block to hold them from sliding entirely through the passages and locating them relatively to the block, a block of insulation slidably fitting the outer section and having 90 wire passages therethrough, the wire passages being arranged to receive the inner wire engaging ends of the plug terminals, and means for holding the sections of the case in assembled relation and thereby holding 95 the blocks of insulation and the plug terminals in position.

4. An electric plug including a case having tubular telescoping sections, a block of insulation slidably mounted in the inner section and having passages therethrough, plug terminals extending through said passages and provided with means for engaging the block to hold them from sliding entirely through the passages and locating them relatively to the block, a block of insulation slidably fitting the outer section and having wire passages therethrough, the wire passages being arranged to receive the inner wire engaging ends of the plug terminals, 115 one of the blocks of insulation having a projection and the other having a recess for receiving the projection when the parts are assembled, and means for holding the sections of the case in assembled relation and thereby holding the blocks of insulation and the plug terminals in position.

5. An electric plug comprising a case having tubular telescoping sections, a block of insulation slidably mounted in the inner section and having passages therethrough, plug terminals extending through said passages and provided with means for engaging the block to hold them from sliding entirely through the passages and locating them 125 rela-

tively to the block, a block of insulation slidably fitting the outer section and having wire passages therethrough, the wire passages being arranged to receive the inner wire en-

5 gaging ends of the plug terminals, the block of insulation within the inner section having an axial projection, and the block within the outer section having a recess for receiving said projection, and means for holding the 10 sections of the case in assembled relation and thereby holding the blocks of insulation and the plug terminals in position.

6. An electric plug comprising a case having tubular telescoping sections, a block of 15 insulation slidably mounted in the inner section and having passages therethrough, plug terminals extending through said passages and provided with means for engaging the block to hold them from sliding entirely 20 through the passages and locating them relatively to the block, a block of insulation slidably fitting the outer section and having wire passages therethrough, the wire passages being arranged to receive the inner wire 25 engaging ends of the plug terminals, the block within the outer section abutting against the end of the inner section of the case when the parts are assembled, and means for holding the sections of the case in 30 assembled relation and thereby holding the block of insulation and the plug terminals in position.

7. An electric plug comprising a case having tubular telescoping sections, a block of 35 insulation slidably mounted in the inner section and having passages therethrough, plug terminals extending through said passages and provided with means for engaging the block to hold them from sliding entirely 40 through the passages and locating them relatively to the block, a block of insulation slidably fitting the outer section and having wire passages therethrough, the wire passages being arranged to receive the inner wire engaging 45 ends of the plug terminals, the blocks having an interfitting recess and projection, and the block within the outer section of the case abutting against the end of the inner section of the case when the parts are assembled, and means for holding the sections of the case in assembled relation and thereby holding the blocks of insulation and the plug terminals in position.

8. An electric plug comprising a case having tubular telescoping sections, a single 50 block of insulation mounted in each section, plug terminals slidably mounted in the block in the inner section, the block in the outer

section normally holding the terminals from displacement, and means carried by the block 60 in the inner section for locking the sections together.

9. An electric plug comprising a case having tubular telescoping sections, terminal, supporting and retaining means slidably 65 mounted in the case and terminals slidably mounted in the supporting and retaining means, and means self-contained with the terminal supporting means within the inner section for holding the sections together and 70 the parts therein in an assembled relation.

10. An electric plug comprising a case having tubular telescoping sections, terminal supporting and retaining means slidably 75 mounted in the case, and terminals slidably mounted in the supporting means, and means self-contained with the terminal supporting means within the inner section, for holding the sections together and the parts therein in an assembled relation, said holding means 80 comprising a wedge coacting with the inner face of the outer section and a wedge operating member accessible through the outer end of the inner section.

11. An electric plug comprising a case 85 having tubular sections, one telescoping into the other, a block of insulation mounted in each section and slidably mounted therein, the blocks having aligned passages therethrough, terminals mounted in the passages 90 and having shoulders located between the blocks for holding the terminals from displacement, and means for holding the sections together.

12. An electric plug comprising a case 95 having tubular sections, one telescoping into the other, a block of insulation mounted in each section and slidably mounted therein, the blocks having aligned passages therethrough, terminals mounted in the passages 100 and having shoulders located between the blocks for holding the terminals from displacement, a shoulder for locating the position of the block in the inner section, the block in the outer section abutting against 105 the inner end of the inner section, and the outer section having a shoulder for locating the block therein, and means carried by the block within the inner section for securing the sections together. 110

In testimony whereof, I have hereunto signed my name, at Syracuse, in the county of Onondaga and in the State of New York, this 10th day of October, 1927.

RAYMOND H. OLLEY.
